UNITED STATES PATENT OFFICE

2,254,794

FEEDING MECHANISM FOR SEWING MACHINES

Frederic M. Card, Bridgeport, Conn., assignor to
The Singer Manufacturing Company, Elizabeth, N.J., a corporation of New Jersey

Original application April 1, 1939, Serial No. 265,397. Divided and this application November 14, 1939, Serial No. 304,285.

16 Claims. (Cl. 112—210)

This is a division of my prior patent application Serial No. 265,397, filed Apr. 1, 1939, the present invention relating to feeding mechanisms for sewing machines and having for its primary object to provide comparatively quiet running and durable means for automatically controlling the work-advancing movements of the feeding mechanism of a sewing machine, at high speeds of operation of the machine.

More specifically, the present invention aims to provide means operable at comparatively high speeds for automatically controlling forward and reverse work-advancing movements of a sewing machine feed-dog.

A further object of the invention is to provide convenient means for changing the effective work-feeding movements of a sewing machine feed-dog performed in a complete cycle of operation of automatic controlling means for the feed-dog actuating mechanism.

Other and more specific objects of the invention will be apparent from the following description and claims.

The invention consists in the feed-actuation controlling mechanism as hereinafter described in connection with the accompanying drawings which illustrate a preferred embodiment of the invention and in which:

Fig. 1 represents a vertical longitudinal section, partly in front elevation, of an ornamental-stitch sewing machine containing the improved feeding mechanism. Fig. 2 represents a bottom plan view of the machine. Fig. 3 represents a vertical section through the bracket-arm standard of the machine on substantially the line 3—3 of Fig. 1. Fig. 4 represents a cross-section of the bracket-arm to include both of the cross-shafts which carry the needle-vibration and feed-controlling eccentrics. Fig. 5 is a detail view in front elevation of the feed-indicator disks. Fig. 6 is a diagrammatic representation of the feed-controlling connections.

The sewing machine illustrated in the drawings has the usual work-supporting bed-plate 1, from one end of which rises the tubular standard 2 of a bracket-arm 3 which overhangs the bed-plate 1 and terminates at its free end in a head 4.

Rotatably journaled in the bracket-arm 3, to extend horizontally lengthwise thereof, is a main actuating or needle-reciprocating shaft 5 carrying at one end a belt-pulley 6. At its opposite end, the shaft 5 carries a counterbalanced crank-disk 7 connected by the usual link 8 with a vertically disposed needle-bar 9 carrying at its lower end a needle 10.

The needle-bar 9 is journaled for endwise reciprocation in a laterally swinging frame 11 pivotally hung at its upper end upon a fulcrum-pin 12 within the bracket-arm head 4. The frame 11 is, as usual, provided adjacent its lower end with an arcuate slot 13 to receive a guide-stud 14, and is also pivotally connected by a screw 15 to one end of a needle-bar vibrating pitman 16. At its opposite end, the pitman 16 has a split strap 17 embracing a rotary needle-vibrating eccentric 18 constructed substantially as more fully disclosed in the U. S. patent to C. F. Gray, No. 1,020,089, Mar. 12, 1912. In general, the eccentric 18 has an enlarged shaft-aperture 19 and extends laterally from a frame 20 adjustably carried by a disk 21 secured by a screw 22 upon a cross-shaft 23. The cross-shaft 23 is disposed below and substantially normal to the needle-reciprocating shaft 5, being journaled at the front of the bracket-arm 3 in a bearing provided by a detachable cap-plate 24 and at its rearward end in a frame-boss 25. Adjacent the eccentric 18, there is secured to the cross-shaft 23 a gear-wheel 26 driven by a spiral-gear 27 carried by the needle-reciprocating shaft 5.

The spiral-gear 27 is preferably secured upon the shaft 5 to provide for angularly adjusting said gear 27, thereby to change the timing of the eccentric 18. To this end, the spiral-gear 27 has a hub 28 extending into an annularly recessed collar 29 secured by screws 30 upon the shaft 5, said collar 29 being secured to the gear-hub 28 by set-screws 31. By freeing the set-screws 31, the shaft 5 and spiral-gear 27 may be relatively rotated to change the timing of the eccentric 18, the gear-hub 28 being preferably provided with spanner-apertures 32 to receive a suitable tool for effecting adjustment of the spiral-gear 27.

In the present case, the ratio of the gears 26 and 27 is such that the cross-shaft 23 rotates once for six rotations of the needle-reciprocating shaft 5. Consequently, the needle 10 reciprocates six times in each complete rotation of the eccentric 18, i. e., the needle reciprocates three times while moving laterally in one direction and three times in its return lateral movement to complete a six-stitch cycle. The amplitude of the complete lateral vibration of the needle, or, in other words, the width of the ornamental seam is determined by adjustment of the eccentricity of the eccentric 18, which may be effected by means of the usual regulating spindle 33, as disclosed in said prior Patent No. 1,020,089.

Cooperating with the needle 10, in the formation of lock-stitches, is a loop-taker in the form

of the usual rotary hook 34 having its axis of rotation substantially parallel to the cross-shaft 23, whereby the rotary hook beak rotates in a plane parallel to the plane of lateral vibration of the needle. The rotary hook 34 is carried by a shaft 35 rotatably journaled in a bushing 36 secured in a lug 37 at the under side of the bed-plate 1. Suitably secured to the hook-shaft 35 is a bevel-gear 38 in mesh with a similar gear 39 carried by one end of a rotary hook actuating shaft 40. The shaft 40 extends horizontally lengthwise of the bed-plate 1 and is journaled for rotation in a tubular feed-lift rock-shaft 41 which, in turn, is journaled to rock in spaced bearing-lugs 42 and 43 depending from the bed-plate 1. At its end opposite to the bevel-gear 39, the hook-actuating shaft 40 carries a pulley 44 connected by a clip-belt 45 to a pulley 46 carried by the needle-reciprocating shaft 5, the pulleys 44 and 46 being proportioned so that the hook-actuating shaft 40 rotates twice for each rotation of its driving shaft 5.

The work is advanced by a feed-dog 47 of the drop-feed type, said feed-dog being opposed by a suitable presser-foot and operating through slots provided in a throat-plate 48, secured upon the bed-plate 1 and having the usual needle-slot 49. The feed-dog 47 is carried by a feed-bar 50 having a slot 51 receiving a slide-block 52 connected by a pivot-bolt 53 to a crank-arm 54 clamped upon one end of the feed-lift rock-shaft 41. Secured upon said feed-lift rock-shaft 41, at the opposite end thereof, is a crank-arm 55 connected by a pivot-bolt 56 to the lower end of a pitman 57. The pitman 57 extends upwardly within the arm-standard 2 and has, at its upper end, a strap embracing a feed-lift eccentric 58 carried by the actuating shaft 5. It will therefore be understood that the feed-dog 47 is raised and lowered once for each reciprocation of the needle.

The rearward end of the feed-bar 50 is pivotally supported by and between the upstanding arms 59 at one end of a feed-advance rock-shaft 60, disposed in substantial parallelism with the feed-lift rock-shaft 41 and journaled in bearing-lugs 61 and 62 depending from the bed-plate 1. Clamped upon the opposite end of the feed-advance rock-shaft 60 is a depending crank-arm 63 connected by a pivot-bolt 64 to one end of a link 65, of which the opposite end is connected by a pivot-bolt 66 to a slide-block 67. The slide-block 67 is shiftably disposed in a segmental guideway 68 provided in a rocking-member 69 having a fulcrum-pin 70 extending laterally from said member substantially medianly between the ends thereof. The fulcrum-pin 70 is journaled for rocking movements in an apertured boss 71 at the lower end of a bracket 72 secured by screws 73 to the under side of the bed-plate 1.

The rocking-member 69 has an ear 74 to which is pivotally secured, by a screw 75, the lower end of a pitman 76. At its upper end, the pitman 76 has a strap embracing an adjustable feed-advance eccentric 77 carried by the needle-reciprocating shaft 5. The adjustable eccentric 77 is constructed, in the present case, substantially in accordance with the disclosure in the U. S. patent to J. H. Stearns, No. 2,029,278, Jan. 28, 1936, although any other suitable or desired form of adjustable eccentric may be employed. From the foregoing description, it will be understood that the feed-dog 47 derives work-advancing and return movements of variable amplitude from the eccentric 77 and that said work-advancing movements are timed to occur when the

feed-dog 47 is raised by the feed-lift mechanism actuated by the feed-lift eccentric 58.

In order to control the effective action of the feed-dog 47 automatically, the slide-block carrying link 65 is connected by a ball-joint 78 to the lower end of a link 79 reciprocating endwise within the arm-standard 2. At its upper end, the link 79 is connected by a ball-joint 80 to an arm 81 of a two-armed lever 81, 82 fulcrumed upon a pivot-screw 83 threaded into the inner wall of the bracket-arm 3, the fulcrum-axis of the lever 81, 82 being substantially parallel to the cross-shaft 23. The arm 82 of the lever 81, 82 is pivotally connected to the lower end of a pitman 84 having a strap 85 embracing a feed-controlling eccentric 86. As illustrated more particularly in Fig. 4 of the drawings, the eccentric 86 is secured by a set-screw 87 upon a shoulder cross-shaft 88 journaled at its rearward end in a bushing 89 suitably fixed in an aperture in the rear wall of the bracket-arm 3, the cross-shaft 88 being disposed above the needle-reciprocating shaft 5 and in substantial parallelism with the cross-shaft 23. The forward reduced portion of the cross-shaft 88 is journaled in a shaft-sleeve 90 which is itself journaled for rotation in a bearing-bushing 91 suitably fixed in the front wall of the bracket-arm 3.

Secured upon the sleeve 90, by a set-screw 92, is the hub 93 of a spiral gear 94 in mesh with a spiral pinion 95 suitably secured upon the needle-reciprocating shaft 5, the ratio of the gears 94 and 95 being such that the cross-shaft 88 rotates once for three rotations of the needle-reciprocating shaft 5. The spiral gear 94 preferably has its side face annularly recessed adjacent the feed-controlling eccentric 86 to receive a disk-flange 96 of said eccentric.

At the front side of the bracket-arm 3, the shaft-sleeve 90 has a disk-flange 97 preferably having a beveled indexed periphery and provided with a series of apertures 98. Adapted to releasably enter any one of said apertures 98 is a coupling-pin 99 extending from a side face of a coupling-disk 100 secured by a key 101 upon the shaft 88 for rotation therewith, but permitting limited movement of the coupling-disk 100 endwise of said shaft. The coupling-disk 100 has a knurled head 102 centrally apertured to receive the head 103 of a screw threaded into the forward end of the cross-shaft 88, the screw-head 103 serving as an abutment for a spring 104 which functions to hold the coupling-disk 100 yieldingly in contact with the disk-flange 97, with the coupling-pin 99 disposed in one of the disk-flange apertures 98. By uncoupling the disk-flange 97 and coupling-disk 100, the cross-shaft 88 may be turned to change the timing of the eccentric 86, as will be self-evident. An angular cover-plate 105 is detachably secured upon the bracket-arm 3 and provides for access to the mechanism within the bracket-arm.

The described feeding mechanism is so designed that in one complete rotation of the feed-controlling eccentric the work is fed twice forwardly and once backwardly. By employing an eccentric for the purpose described, instead of a pattern-cam, the speed of operation of the machine may be substantially increased beyond the maximum speed capacity of prior machines while, at the same time, reducing objectionable noise and wear. Furthermore, by the provision for convenient adjustments of the relative timing of the needle-vibrating and feed-controlling

eccentrics, a large variety of ornamental seams may be readily produced.

The length of the stitches is not only dependent upon the amplitude of lateral vibration of the needle 10 between successive work-penetrations thereof, but also upon the feeding mechanism, which is illustrated diagrammatically in Fig. 6 of the drawings. The feed-dog 47, carried by the feed-bar 50 is, as usual, raised and lowered by the feed-lift eccentric 58 having the described connections with the slide-block 52, and forward and backward movements are imparted to said feed-dog 47 by the feed-advance eccentric 71 which functions to rock the segmental guideway 68 about its fulcrum-axis 70. In any off-center position of the slide-block 67 in its guideway 68, the rocking movements of said guideway are transmitted by the link 65 to the feed-rocker 59, 60, 63, as will be readily understood.

The shifting movements of the slide-block 67 in the guideway 68 are controlled by the feed-controlling eccentric 86 through the described connections with said slide-block 67, the throw of the eccentric 86 being such that the slide-block 67 travels from one side to the other of the fulcrum-axis 70 of the guideway 68. In the position *x*, Fig. 6, of the point of maximum eccentricity of the eccentric 86, the slide-block 67 is substantially at *x'* in the portion of the guideway 68 above the fulcrum-axis thereof and the feed-dog 47 is in a median position of its forward work-advancing movement. In a one-third revolution of the eccentric 86, from the position *x* to position *y* of its point of maximum eccentricity, the slide-block 67 travels downwardly across the fulcrum-axis 70 in the guideway 68, during the return movement of the feed-dog 47, to bring said slide-block to the point *y'* in the succeeding median position of the feed-dog 47 in which the work is fed backwardly.

In the next one-third revolution of the eccentric 86, from *y* to *z*, the slide-block travels upwardly across the fulcrum-axis 70 of the guideway 68 to substantially the point *z'*, during the time that the feed-dog 47 has its return idle movement to a median position of forward feeding movement. In the final one-third revolution of the eccentric 86, from *z* to the starting point *x*, the slide-block 67 travels slightly upwardly and then downwardly to the position *x'* thereof wherein the feed-dog 47 is again advancing the work forwardly.

From the foregoing description, it will be understood that different varieties of seams may be produced by merely adjusting the timing of the feed-controlling eccentric 86, which may be conveniently effected by pulling forwardly upon the coupling-disk head 102, partly turning the feed-controlling cross-shaft 88 and recoupling the disks 97, 100, in a newly selected relative position thereof. By means of any suitable indicator-expedient, the desired relative position of the disks 97, 100, may be obtained with precision.

Still further varieties of ornamental seams may be produced by adjusting the timing of both the needle-vibrating eccentric 18 and the feed-controlling eccentric 86, as will be apparent. In connection with the timing adjustments described, it is to be understood that said adjustments do not interfere with the complementary action of the reciprocating needle 10 and rotating loop-taker 34 to form stitches. The loop-taker 34 accommodates the maximum lateral throw of the needle 10 effected by the needle-vibrating eccentric 18 of the machine. For still

wider lateral throws of the needle, any well-known or other suitable device may be employed either to accelerate and retard the loop-taker or to bodily shift the loop-taker laterally in timed relation with the needle.

5 It is also to be understood that the timing adjustments of the feed-controlling eccentric 86 do not interfere with the proper feeding of the work, because the timing of the rocking-member 69 to actuate the feed-dog 47 and the timing 10 of the feed-lift mechanism is unaffected by said timing adjustments of the feed-controlling eccentric 86.

Having thus set forth the nature of the invention what I claim herein is:

- 15 1. In a sewing machine, stitch-forming mechanism including a reciprocating needle, a feed-dog, actuating mechanism for imparting operative work-advancing movements to said feed-dog, a rotary feed-controlling eccentric in addition to said actuating mechanism, means actuated by said eccentric and operatively connected to said actuating mechanism for controlling the effective action thereof, and means for rotating said eccentric continuously in one direction.
- 20 2. In a sewing machine, stitch-forming mechanism including a reciprocating needle, a feed-dog, actuating mechanism for imparting operative work-advancing movements to said feed-dog, a rotary feed-controlling eccentric in addition to said actuating mechanism, means actuated by said eccentric and operatively connected to said actuating mechanism for controlling the direction of feed of the work, and driving means for rotating said eccentric continuously in one direction.
- 25 3. In a sewing machine, stitch-forming mechanism including a reciprocating needle, a rotary needle-reciprocating shaft, operative connections with said shaft for reciprocating said needle, a feed-dog, actuating mechanism for imparting operative work-advancing movements to said feed-dog, a rotary feed-controlling eccentric operatively connected to said actuating mechanism, and means for rotating said eccentric at one-third the speed of rotation of said needle-reciprocating shaft.
- 30 4. In a sewing machine, stitch-forming mechanism including a reciprocating needle, a feed-dog, actuating mechanism for imparting operative work-advancing movements to said feed-dog, a rotary feed-controlling eccentric, means actuated by said eccentric and operatively connected to said actuating mechanism for controlling the direction of feed of the work, and means for rotating said eccentric in timed relation to successively feed the work twice forwardly and once backwardly.
- 35 5. In a sewing machine, stitch-forming mechanism including a reciprocating needle, a work-advancing feed-dog, a feed-bar carrying said feed-dog, feed-advance and feed-lift mechanisms connected to said feed-bar and effective to impart work-feeding movements to said feed-dog, a rotary feed-controlling eccentric, means actuated by said eccentric and operatively connected to said feed-advance mechanism for controlling the work-advancing action of said feed-dog, and driving means for rotating said eccentric continuously in one direction.
- 40 6. In a sewing machine, stitch-forming mechanism including a reciprocating needle, a feed-dog, actuating mechanism for imparting operative work-advancing movements to said feed-
- 45
- 50
- 55
- 60
- 65

dog, a rotary feed-controlling eccentric in addition to said actuating mechanism, means actuated by said eccentric and operatively connected to said actuating mechanism for controlling the direction of feed of the work, driving means for rotating said eccentric continuously in one direction, and means providing for adjusting the timing of said eccentric.

7. In a sewing machine, stitch-forming mechanism including a reciprocating needle, a feed-dog, a feed-bar carrying said feed-dog, feed-advance and feed-lift mechanisms connected to said feed-bar and effective to impart work-feeding movements to said feed-dog, a rotary feed-controlling shaft, driving means for rotating said shaft, a feed-controlling eccentric, manually adjustable means for securing said eccentric for rotation with said shaft in differently timed positions of said eccentric, and means actuated by said eccentric and operatively connected to said feed-advance mechanism for controlling the work-feeding action of said feed-dog.

8. In a sewing machine, stitch-forming mechanism including a reciprocating needle, a rotary needle-reciprocating shaft, operative connections with said shaft for reciprocating said needle, a feed-dog, a feed-bar carrying said feed-dog, feed-advance and feed-lift mechanisms connected to said feed-bar and effective to impart work-feeding movements to said feed-dog, a rotary feed-controlling shaft, driving means for rotating said feed-controlling shaft at a slower speed than the speed of rotation of said needle-reciprocating shaft, an eccentric, manually adjustable means for securing said eccentric for rotation with said feed-controlling shaft in differently timed positions of said eccentric, and means actuated by said eccentric and operatively connected to said feed-advance mechanism for controlling the work-feeding action of said feed-dog.

9. In a sewing machine, stitch-forming mechanism including a reciprocating needle, a feed-dog, actuating mechanism for imparting operative work-advancing movements to said feed-dog, coaxially disposed feed-controlling shafts, driving connections with one of said shafts for rotating the same, an eccentric carried by the other of said shafts for rotation therewith, manually releasable coupling means connecting said shafts for unison rotation and providing for changing the timing of said eccentric with respect to said driving means, and means actuated by said eccentric and operatively connected to said feed-dog actuating mechanism for controlling the work-feeding action of the feed-dog.

10. In a sewing machine, stitch-forming mechanism including a reciprocating needle, a feed-dog, actuating mechanism for imparting operative work-advancing movements to said feed-dog, coaxially disposed feed-controlling shafts, driving connections with one of said shafts for rotating the same, an eccentric carried by the other of said shafts for rotation therewith, relatively movable coupling-disks carried by said shafts, one of said disks having a coupling-pin and the other of said disks having a plurality of circumferentially disposed apertures adapted to receive said coupling-pin, yielding means normally holding said disks in coupled engagement and providing for relatively turning said shafts to adjust the timing of said eccentric, and means actuated by said eccentric and operatively connected to said feed-dog actuating mechanism for controlling the work-feeding action of the feed-dog.

11. In a sewing machine, stitch-forming mechanism including a reciprocating needle, a feed-dog, a feed-bar carrying said feed-dog, feed-lift actuating mechanism operatively connected to said feed-bar, a feed-advance rocker operatively connected to said feed-bar, a rocking member provided with a guideway, means for rocking said member, a slide-block shiftably disposed in said guideway and connected to said feed-advance rocker to impart feeding and return movements to said feed-dog, a rotary feed-controlling eccentric, a strap embracing said eccentric and operatively connected to shift said slide-block in said guideway, and driving means for rotating said eccentric continuously in one direction.

12. In a sewing machine, stitch-forming mechanism including a reciprocating needle, a feed-dog, a feed-bar carrying said feed-dog, feed-lift actuating mechanism operatively connected to said feed-bar, a rocking member provided with a guideway extending across the fulcrum-axis of said member, means for rocking said member, a slide-block shiftably disposed in said guideway and operatively connected to said feed-bar to impart feeding and return movements to said feed-dog in an off-center position of said slide-block in said guideway, a rotary feed-controlling eccentric, a strap embracing said eccentric and operatively connected to shift said slide-block in said guideway from one to the other side of the fulcrum-axis of said rocking member, and driving means for rotating said eccentric continuously in one direction.

13. In a sewing machine, stitch-forming mechanism including a reciprocating needle, a feed-dog, a feed-bar carrying said feed-dog, feed-lift actuating mechanism operatively connected to said feed-bar, a rocking member provided with a guideway extending across the fulcrum-axis of said member, means for rocking said member, a slide-block shiftably disposed in said guideway and operatively connected to said feed-bar to transmit the rocking movements of said member to said feed-dog in an off-center position of said slide-block in said guideway, a feed-controlling element operatively connected to shift said slide-block in said guideway from one to the other side of the fulcrum-axis of said rocking member, and means for actuating said feed-controlling element in timed relation to the rocking movements of said member to impart successively two forward and one backward work-feeding movements to said feed-dog.

14. In a sewing machine, stitch-forming mechanism including a reciprocating needle, a feed-dog, a feed-bar carrying said feed-dog, feed-lift actuating mechanism operatively connected to said feed-bar, a rocking member provided with a guideway extending across the fulcrum-axis of said member, means for rocking said member, a slide-block shiftably disposed in said guideway and operatively connected to said feed-bar to transmit the rocking movements of said member to said feed-dog in an off-center position of said slide-block in said guideway, a rotary feed-controlling element operatively connected to shift said slide-block in said guideway from one to the other side of the fulcrum-axis of said rocking member, and driving means for rotating said feed-controlling element once for three complete rocking movements of said rocking member.

15. In a sewing machine, stitch-forming mechanism including a reciprocating needle, a rotary needle-reciprocating shaft, operative connections with said shaft for reciprocating said needle, a

work-advancing feed-dog a feed-bar carrying said feed-dog, a rocking member provided with a segmental guideway extending across the fulcrum-axis of said member, means for rocking said member in opposite directions once for each complete reciprocation of said needle, a slide-block shiftably disposed in said guideway and operatively connected to said feed-bar to transmit the rocking movements of said member to said feed-dog, a rotary feed-controlling shaft, means for rotating said feed-controlling shaft at one-third the speed of rotation of said needle-reciprocating shaft, a feed-controlling eccentric secured for rotation with said feed-controlling shaft, and a strap embracing said eccentric and operatively connected to shift said slide-block in said guideway across the fulcrum-axis of said rocking member.

16. In a sewing machine, stitch-forming mechanism including a reciprocating needle, a rotary needle-reciprocating shaft, operative connections

with said shaft for reciprocating said needle, a work-advancing feed-dog, a feed-bar carrying said feed-dog, a rocking member provided with a segmental guideway and having a fulcrum-axis 5 intersecting said guideway, means for rocking said member in opposite directions once for each complete reciprocation of said needle, a slide-block shiftably disposed in said guideway and operatively connected to said feed-bar to transmit 10 the rocking movements of said member to said feed-dog, a rotary feed-controlling shaft extending crosswise of said needle-reciprocating shaft, means for rotating said feed-controlling shaft once for three rotations of said needle-reciprocating shaft, a feed-controlling eccentric secured for rotation with said feed-controlling shaft, and means actuated by said eccentric and 15 operatively connected to shift said slide-block in said guideway.

FREDERIC M. CARD.
